US0D1088304S

(12) **United States Design Patent** (10) Patent No.: **US D1,088,304 S**
(45) Date of Patent: **** Aug. 12, 2025**

(54) **CANDLE HOLDER**

(71) Applicant: **TURKIYE SISE VE CAM FABRIKALARI ANONIM SIRKETI, Istanbul (TR)**

(72) Inventor: **Edizalp Akin, Istanbul (TR)**

(**) Term: **15 Years**

(21) Appl. No.: **35/522,757**

(22) Filed: **Jun. 29, 2024**

(80) **Hague Agreement Data**

Int. Filing Date: **Jun. 29, 2024**

Int. Reg. No.: **DM/241146**

Int. Reg. Date: **Jun. 29, 2024**

Int. Reg. Pub. Date: **Oct. 25, 2024**

(30) **Foreign Application Priority Data**

Dec. 29, 2023 (TR) 2023/014225

(51) **LOC (15) Cl.** **26-01**

(52) **U.S. Cl.**

USPC **D26/9**

(58) **Field of Classification Search**

USPC D26/9-23, 88; D11/146

CPC F21V 35/00

See application file for complete search history.
